UNITED STATES PATENT OFFICE.

LOUISE R. SEWARD, OF NEW YORK, N. Y.

DESIGN FOR A COLLAR-PROTECTOR.

SPECIFICATION forming part of Design No. 33,718, dated December 11, 1900.

Application filed June 2, 1900. Serial No. 18,908. Term of patent 7 years.

To all whom it may concern:

Be it known that I, LOUISE R. SEWARD, a citizen of the United States, and a resident of the city of New York, (New Brighton,) borough of Richmond, in the county of Richmond and State of New York, have invented and produced a new and original Design for a Collar-Protector, of which the following is a full, clear, and exact description.

Reference is to be had to the accompanying drawing, forming a part of this specification, in which the figure is a side view of a collar-protector, showing my design.

The leading feature of my design is its marginal contour or shape. This generally is that of an attenuated oval, both sides being convex, one being somewhat flatter than the other, and the side which is least flat having in its middle a reëntrant V-shaped notch, re-

solving the two portions of the collar-protector on opposite sides of the minor axis into exactly symmetrical halves in which all marginal lines are convex or inwardly-curving lines, terminating at the ends in sharply-rounded corners approximating angular points.

Having thus described my invention, I claim as new and desire to secure by Letters Patent—

The design for a collar-protector as herein shown and described.

In testimony whereof I have signed my name to this specification in the presence of two subscribing witnesses.

LOUISE R. SEWARD.

Witnesses:

JNO. M. RITTER,
C. R. FERGUSON.
